LABELING MACHINE

George W. von Hofe, Bound Brook, N. J., assignor
to New Jersey Machine Corporation, Hoboken,
N. J., a corporation of New Jersey

Application March 23, 1945, Serial No. 584,373

5 Claims. (Cl. 216—56)

1

The invention relates to labeling machines designed for adhesively applying labels or their equivalents to sheets of material as exemplified for instance by cards such as greeting cards, fabrics, or pieces thereof, such as swatches and the like.

The object of the invention is to provide such labeling machines with a novel supporting means located at the applying station of the machine for supporting a supply of sheets of material in label-receiving position, and capable of being operated to present successive sheets in label-receiving relation to the label-applying means of the machine.

The invention contemplates further the provision of a novel support for a stack of sheets of material at the applying station of the machine, and manually-operated means for intermittently raising said support to thereby maintain efficient operative relation between the label-applying means of the machine and successive terminal sheets of material at the upper end of said stack.

Other objects of the invention will appear from the description hereinafter and the features of novelty will be pointed out in the claims.

In the accompanying drawings, which illustrate an example of the invention without defining its limits,

Fig. 1 is a front elevation of the novel supporting means, and

Fig. 2 is a side elevation thereof.

The novel supporting means is particularly adapted for operative association with labeling machines of the type illustrated in my United States patent, No. 2,227,816, of January 7, 1941.

Such machines comprise a suitable frame 5 on which the labeling instrumentalities are mounted, for instance, as disclosed in the previously-mentioned patent. Such instrumentalities include a suction head or equivalent label transfer device 6 whereby the labels or the like are transferred in succession, for instance, from a supply stack of such labels or the like to an applying station at which the novel supporting means is located. In the course of the aforesaid transfer, the successive labels or the like may be passed in adhesive-receiving relation with an adhesive-applying roller 7 and receive a coating of adhesive therefrom.

The labeling machine otherwise may include all of the mechanism disclosed in my previously-mentioned patent or said machine may be of special construction including features specific to itself without in any way affecting the operative efficiency of the novel supporting means.

2

Broadly speaking, such supporting means comprises a supporting member 8 on which the elements to be labeled, such as a supply of sheets of material are located in label-receiving position. Furthermore, the novel supporting means comprises means whereby successive sheets of material are presented in label-receiving relation to the label-applying means of the machine. In the specific example illustrating the invention, the sheets of material are arranged on the supporting member 8 in the form of an upright stack, and operating means is provided for periodically raising said supporting member to thereby maintain efficient operative relation between the label-applying means of the machine and successive terminal sheets of material at the upper end of said stack. The aforesaid operating means may be automatically controlled and actuated, at predetermined intervals in any convenient manner as by hydraulic, electric, or other mechanism, or as shown in the illustrated example, said operating means may be manually actuated.

The supporting member 8 is fixed upon the upper end of a rack 9 which is slidably mounted for vertical movement and guided in a guide bracket 9—a carried by a horizontal table 10 supported by means of suitable brackets 11 bolted or otherwise secured upon the frame 5 of the machine, as shown in Fig. 2. In the illustrated example, foot-operated means is provided for manually elevating the supporting member 8 intermittently at required intervals to maintain successive terminal sheets of material or their equivalent, at the upper end of said stack, in proper label-receiving position relatively to the label-applying means of the machine. In its illustrated form, the foot-operated means comprises an operating lever 12 fulcrumed at 13—a upon a bracket 13 which may form part of or be secured to the previously-mentioned bracket 11. A spring 14 has its one end connected with a fixed stud 15 and its other end attached at 16 to the lever 12 near one end thereof, for returning said lever 12 and its associated parts to normal position. The lever 12 carries an operating pawl 17 which is pivotally mounted thereon at 18 and has its operating end maintained in meshing engagement with the rack 9 by means of a spring 19 bearing against said pawl 17 and against a projection 19—a fixed upon the lever 12. A cooperating stop-pawl 20 is pivotally mounted at 21 upon the bracket 13, and likewise has its operating end in meshing engagement with the rack 9 for fixing the latter against unintentional re-

turn movement. A spring 22 located between a fixed abutment 23 and the stop-pawl 20, yieldingly maintains the latter in its operative association with the rack 9.

For the purpose of rocking the lever 12 and thereby actuating the operating pawl 17 in a manner to intermittently move the rack 9 and with it the supporting member 8, in an upward direction, the lever 12 is connected by means of a link 24, with a pedal-lever 25 pivoted at 26 upon a lug 27 fixed upon the frame 5 of the machine. The pedal-lever 25 preferably carries a treadle 28 at its free end to facilitate the pivotal operation of said lever 25.

For the purpose of maintaining the sheets of material in the intended stack formation on the supporting member 8, upright guide members 29 are adjustably mounted on the table 10 and project upwardly in perpendicular relation to the latter and in parallelism with each other as shown in Figs. 1 and 2. To enable the guiding members 29 to be adjusted to different positions on the table 10, the latter is provided with slots 30 through which the guide members 29 project, said guide members 29 preferably being slidably mounted in bearings 31 comprising alining parts of brackets 32 adjustably mounted in surface engagement with the lower face of the table 10 as shown in Figs. 1 and 2. Each bracket 32 is provided with a slot 33 for the accommodation of a screw 34 extending upwardly through the respective slots 30 of the table 10 and each provided with a wing-nut 35, whereby the associated bracket 32 is fixed in an adjusted position. Preferably, the guide members 29 are yieldingly slidable in the bearings 31 under the influence of coil springs 36, bearing with one end against pins 37 fixed on the associated guide members 29, and with the other end engaging the lower bearings 31 of the cooperating brackets 32.

In the preferred arrangement, means is provided for locking the rack 9 and supporting member 8 against movement in either direction should this be desired or necessary. This means in its illustrated form comprises a pinion 38 carried by a shaft 39 and meshing with the rack 9. The shaft 39 is journaled in a bearing 40 fixed on the bracket 13 and has its outer end screw-threaded for the accommodation of an internally-threaded locking sleeve 41 preferably including a hand wheel 42 to facilitate the manipulation thereof.

In practice, a plurality of sheets of material or other elements A to which the labels B or their equivalent are to be applied, are arranged in the form of an upright stack on the supporting member 8, between the guide members 29, with the terminal sheet of material A at the upper end of said stack at the proper label-receiving level. Successive labels B or their equivalent, are removed from a conventional supply-stack thereof located at the customary pick-up station as shown in my previously-mentioned patent, by means of the label transfer device 6 which, as shown in my previously-mentioned patent, may be in the nature of a suction head, and transferred in adhesive-receiving relation with the adhesive-applying roller 7, to receive a coating of adhesive therefrom. The transfer of each label B is continued to bring the label transfer device 6 and the adhesive-coated label B carried thereby, into applying relation to the terminal sheet of material A at the top of the stack on the supporting member 8. The label transfer device or suction head 6 is then manipulated to deposit such label B upon the terminal sheet of material A after which said

label transfer device or suction head 6 is operated in a return direction into operative relation with the supply stack of such labels or their equivalent, at a level above that of the adhesive-applying roll 7. The initial deposit of a given label or its equivalent upon the terminal sheet of material A at the upper end of the stack on the supporting member 8, may subsequently be followed by the application of said given label B to said sheet of material A is completed and the latter is removed in any convenient manner.

All of the operations so far described correspond to those set forth in my patent hereinbefore referred to.

The aforesaid operations are repeated with successive labels or their equivalent and successive terminal sheets of material. As previously indicated, the latter are removed from the stack on the supporting member 8, as soon as each applying operation has been completed. As a result, the stack of sheets of material on the supporting member 8, is gradually reduced in height so that the level of successive sheets of material is progressively lowered.

At such intervals, as may be necessary, foot pressure is exerted on the treadle 28, to pivotally rock the pedal lever 25 on its pivot 26 in a downward direction, and to exert a downward pull upon the link 24. This downward pull of the latter is transmitted to the lever 12, and rocks the same on its pivot 13, in a direction to cause the operating pawl 17 to exert an upward push on the rack 9 whereby the supporting member 8 and the stack of sheets of material A thereon, are elevated to an extent necessary to again bring the terminal sheet of material A at the upper end of the stack of such sheets, to the proper label-receiving position. As foot pressure is removed, from the treadle 28, the spring 14 will rock the lever 12 and its associated elements in a return direction. This causes the operating pawl 17 to correspondingly slide relatively to the rack 9 in a similar return direction, to thereby bring said operating pawl 17 to a new position on the rack 9 ready for the next operation. In the meantime, the stop-pawl 20 serves to maintain the rack 9 and supporting member 8 with its stack of sheets of material A in the raised position to which it has just been elevated, and to resist the applying pressure of the applying means. These operating cycles are repeated throughout an operative period as will be apparent.

Because of the resilient support of the guide members 29, the latter are enabled to yield downwardly during the label-applying operation.

The novel supporting means including its operating mechanism is simple in construction and may be readily incorporated in existing labeling machines.

The novel means requires no particular supervision and no special skill in its operation, and is controlled by the attendant in an efficient manner, and in the specific form shown, without requiring the hands of said attendant to be used in such control, while the periodic adjustment of the terminal sheet of material at the top of the stack thereof to the proper label-receiving level or position, is being effected.

The arrangement of the parts and the control thereof is of such nature that the applying level of the stack of sheets of material on the supporting member 8 may be maintained at a constant point, in a simple and efficient manner.

The novel means is particularly adapted for

use in the application of labels to fabrics, or samples thereof commonly known as swatches, and for applying tip-ons to greeting cards and the like.

It is to be understood that the term "label" is used herein to include such devices as exemplified by the aforesaid tip-ons and also all equivalents thereof.

Although the present invention has been described in conjunction with a preferred embodiment, it is to be understood that modifications and variations may be resorted to without departing from the spirit and scope of the invention, as those skilled in the art will readily understand. Such variations and modifications are considered to be within the purview and scope of the claims.

I claim:

1. In a labeling machine or the like, the combination of an adjustable supporting member for carrying a stack of elements to be labeled, means operative to apply successively labels to the top elements in the stack on said supporting member, a guide, a rack vertically slideable in said guide and carrying said supporting member, a lever disposed transversely of and adjacent to said rack, means supporting said lever for pivotal movement in a vertical plane, means operable to pivot said lever in one direction from a normal at-rest position, an operating pawl on said lever in operative mesh with the teeth of said rack and cooperating with the latter to lift said supporting member during movement of said lever in the said direction and thereby to raise the stack to bring the uppermost element thereof into label receiving position, and means cooperating with said rack to maintain the latter and said supporting member in adjusted position during the application of a label by said applying means to the uppermost element in the stack.

2. In a labeling machine or the like, the combination of an adjustable supporting member for carrying a stack of elements to be labeled, means operative to successively apply labels to the top elements in the stack on said supporting member, a guide, a member vertically slideable in said guide and carrying said supporting member, means connected to said slideable member and operable intermittently to raise the latter and said supporting member and thereby to raise the stack to bring the uppermost element thereof into label receiving position, and means cooperating with said slideable member to maintain the latter and said supporting means in adjusted position during the application of a label by said applying means to the uppermost element in the stack.

3. In a labeling machine or the like, the combination of an adjustable supporting means for carrying a stack of elements to be labeled, vertically disposed guide means for the elements in said stack, said guide means being mounted for slideable movement in a vertical direction and adapted to yieldingly resist movement from a raised at-rest position, means operative to successively apply labels to the top elements in the stack on said supporting means, said operative means being adapted to engage and depress said

guide means during the label applying step, means connected to said supporting means and operable to raise the latter and thereby raise the stack to bring the uppermost element thereof into label receiving position, and means cooperating with said supporting means to maintain the latter in adjusted position during the application of a label by said applying means to the uppermost element in the stack.

4. In a labeling machine or the like, the combination of an adjustable supporting means for carrying a stack of elements to be labeled, vertically disposed guide means for the elements in said stack, means supporting said guide means for slideable movement in a vertical direction, means for normally maintaining said guide means in raised position and adapted to yieldingly resist movement thereof to a lowered position, means operative to successively apply labels to the top elements in the stack on said supporting means, said operative means being adapted to engage and depress said guide means during the label applying step, means connected to said supporting means and operable to raise the latter and thereby raise the stack to bring the uppermost element thereof into label receiving position, and means cooperating with said supporting means to maintain the latter in adjusted position during the application of a label by said applying means to the uppermost element in the stack.

5. In a labeling machine or the like, the combination of a fixed support, supporting means for carrying a stack of elements to be labeled slideably mounted on said fixed support for movement in a vertical direction, guide means for the elements in said stack slideably mounted on said fixed support for movement in a vertical direction, resilient means for normally maintaining said guide means in raised position and adapted to yieldingly resist movement thereof to a lowered position, means operative to successively apply labels to the top elements in the stack on said supporting means and adapted to engage and depress said guide means during the label applying step, whereby said guide means is moved relative to said supporting means, means connected to said supporting means for moving the latter relative to said guide means so as to raise the stack and thereby bring the uppermost element thereof into label receiving position, and means cooperating with said supporting means to maintain the latter in adjusted position during the application of a label by said applying means to the uppermost element in the stack.
